UNITED STATES PATENT OFFICE.

JOHN BURRY, OF NEW YORK, N. Y.

RECEIVER FOR PRINTING-TELEGRAPHS.

SPECIFICATION forming part of Letters Patent No. 663,859, dated December 18, 1900.

Application filed August 18, 1896. Serial No. 603,136. (No model.)

To all whom it may concern:

Be it known that I, JOHN BURRY, a citizen of the United States, and a resident of New York, (Astoria,) in the county of Queens and State of New York, have invented certain new and useful Improvements in Receivers for Printing-Telegraphs, of which the following is a specification.

This invention relates to new and useful improvements in printing-telegraphs, and especially to a receiver for the same.

The object of my invention is to provide a new and improved printing-telegraph receiver which is simple in construction, not apt to get out of order, can be operated at variable, high, or low speed, requires no skilled operators, and is especially adapted for use on private lines.

The invention consists in the combination, with a type-wheel having a series of circumferential rows of types and mounted to rotate in both directions and to be shifted in the direction of its length, front or back, of means for moving the same by an electric current and magnets.

The invention further consists in the combination, with such type-wheel, of a magnet and coils on the same and an oscillating armature mounted to be influenced and turned in either direction by the electric current passing through the coils, which rotary movements are resisted by a series of resistances, so as to permit of certain turning motion only for a given amount of current and a greater turning motion for a greater amount of current, which turning motions in one direction or the other are transmitted to the type-wheel to turn the same in either direction or to shift the same longitudinally in either direction.

The invention further consists in the combination, with the above elements, of an additional type-wheel and means for using either type-wheel.

The invention also consists in the construction and combination of parts and details, as will be fully described and set forth herein-after and finally pointed out in the claims.

In the accompanying drawings, forming a part of this specification, and in which like letters of reference indicate like parts in all the views, Figure 1 is a perspective view of the motor mechanism of the receiver of my

improved printing-telegraph. Fig. 2 is a vertical longitudinal sectional view of the receiver on the line 2 2 of Fig. 3. Fig. 3 is a plan view of the receiver. Fig. 4 is a vertical transverse sectional view on the line 4 4 of Fig. 3. Fig. 5 is a diagram view of the receiver, showing the circuits. Fig. 6 is a diagram view of the devices for using two type-wheels. Fig. 7 is a diagram view showing relays in the local circuit.

For shifting the type-wheels I do not make use of synchronism or step-by-step or like movements, such as have been used in "tickers" or like printing-telegraphs heretofore; but I make use of two independent electric currents by varying the strength of the same and overcoming, by means of this current, resistances of different strengths, and thereby bringing the type-wheel into different positions corresponding to the different strengths of currents and combinations.

The ends of the two shanks of the permanent magnet A are shaped to form a circular receptacle for a wire coil B, which is fixed in the same, the ends of the coil being connected with a line-wire and earth either in local battery or outside line. An iron armature-core C is mounted loosely in the center of the coil B and is fixed on a shaft C', mounted in a frame C² on the magnet A. On the opposite ends of said core C the two anchor-shaped arms or extensions D D', extending in opposite directions, are fixed. A check-pin E, projecting from the upper edge of the armature D, can move between two stops E' E' for the purpose of limiting the turning motion of the armatures. A transverse arm F is fixed on the shaft C' and is provided in its upper edge, at each side of the shaft C', with one, two, or three or more notches F—in the case shown three on each side—which notches serve to receive the knife-edge pins G', projecting from slides G, suitably guided to move vertically and pulled downward by helical springs G² or analogous devices to rest normally on offsets H of various elevations above the plane of the shaft C'. As shown, the pins G' nearest the shaft C' normally rest on an offset H and on the arm F, the next pins in the direction from the shaft C' to either side on offsets H, higher than the shaft C', and the outermost pins G' rest on still higher offsets H.

When current is passed through the coil B, the shaft C' is turned either to the right or left, according to the sign of the current, and one end of the arm F is moved upward 5 and the other downward. If the current has a certain predetermined strength, it can raise the arm F only sufficiently to overcome the resistance of the corresponding spring G² nearest the shaft to such an extent that the 10 arm F comes in contact with the second pin G' on the same side, but does not act on the pin or lift it off the offset H; but if the strength of the current is increased a predetermined amount the arm F is raised sufficiently 15 to overcome the first and second springs G² on the same side and to come in contact with the outermost pin G', without, however, acting on the same. If the current is still further increased, the arm F is raised 20 sufficiently to lift off all three pins G' and stretch all three springs G² until the check-pin E strikes against the corresponding stop E'. In a like manner the other side of the 25 arm F can be raised. The springs at any one side of the shaft C' only begin to offer resistance as soon as the current turns the shaft C' in such a manner as to lift the corresponding end of the arm F. When the said end of the arm descends to or below the horizontal, the 30 corresponding springs G² cannot act, as their tension is taken up by the offsets H.

The movements of the arm F are not necessarily successive, as described, as sufficient current can be admitted at once to lift either 35 end of the arm F to the extreme position, and the successive movement was only described to explain the operation.

The shaft C' has an arm J, provided on its free end with a segment-rack J', engaging a 40 pinion I' on the shaft I, mounted in a frame I², and on said shaft a type-wheel K is mounted in such a manner that it can slide on the shaft, but is compelled to turn with the same. The type-wheel has a series of annular rows of type characters, there being a like number of type characters in each row, and each circumferential row has twice as many type characters plus one as there are 45 different positions or resistances on each side 50 of the shaft C'. For example, six springs G² are shown in the drawings—that is, three on each side—and consequently there must be seven type characters in each circumferential row. Three different strengths of current 55 are required both for negative and positive, giving six positions, to which must be added the position of rest, which gives seven, as above.

When only two springs or other resistances 60 are provided for each end of the arm F, we have five positions, including the position of rest, and therefore there must be five type characters on each circumferential row on the type-wheel, and when only one spring or other 65 resistance is provided for each end of the arm F we have three positions, and therefore there must be three characters on each circumfer-

ential row of the type-wheel. The type-wheel can thus be turned to present as many longitudinal rows of characters as there are resistances for the arm F plus one, and it now remains to shift the type-wheel longitudinally to bring the circumferential row bearing the desired type character into proper position, the type-wheel being turned circumferentially at the same time for this required character. To produce this longitudinal movement, an additional magnet-coil and armature, &c., are provided, like the one described, at substantially right angles to those described. 70 The arm L of the armature-shaft of this additional magnet A terminates in a hook or bend L', which passes into the central groove between two circumferential rows of type characters, so that when said shaft is turned 75 in one direction or the other it shifts the type-wheel longitudinally a greater or less distance, according to the strength of the current used, and in one direction or the other, accordingly as a positive or negative current 80 is used. With seven circumferential rows of seven type characters each forty-eight positions can be obtained, as there must be a position of rest which corresponds to one character. With five circumferential rows of five 85 characters each twenty-four positions can be obtained, and with three circumferential rows of three characters each eight positions can be obtained.

In addition to above combinations the apparatus can be so arranged as to have a different number of positions by rotation from those obtained by shifting. For example, there may be seven characters in each circumferential row and only five or only three of 90 such rows—that is, the type-wheel would be shifted longitudinally into only five or three positions, respectively.

It is evident that the type-wheel may have more than seven characters in each circumferential row; but this number should preferably be equal to twice the number of strengths of current plus one used for turning, and the number of changes by shifting should be equal to twice the number of 95 strengths of current plus one used for shifting longitudinally.

The receiver must be provided with means for feeding a paper strip, an inking device, and means for pressing the strip of paper 100 against the type-wheel. This may be accomplished in various ways, and many of the old and well-known devices may be used for this purpose; but I prefer to use the mechanism now to be described.

The lever M, pivoted at M', carries at one end the armature M² of the press-magnet M³ and at the other end the block M⁴ for pressing the paper strip N against the type-wheel and inking-ribbon P. The paper band or tape N is 110 wound on a reel N' and passes over the guides N² N² and over the feed-wheel N³ on the end of the shaft O' on which the ratchet-wheel N⁴ is fixed, that is engaged by the hook-pawl N⁵, 120

operated by the lever M and the check-pawl N^6 . The spring-pressed roller N^7 presses the paper strip or tape upon the feed-roller N^3 . A worm O is formed on one end of the shaft O' of the paper-feed wheel N^3 and engages a worm-wheel formed on one of the two spools O^2 , over which the endless inking-ribbon P passes. Each shaft C' carries a disk Q , in the rim of which a piece Q' of insulating material is countersunk in such a manner that said piece is at the top when no current is passing, and on said disk Q a brush R rests, which is non-conductively attached to the frame of the machine. As shown in diagram Fig. 5, the brushes R of both magnets are connected with a local battery T , which in turn is connected with the press-magnet M^3 , and the latter is connected with the frame.

When both brushes R rest on the insulating-pieces Q' , the entire local-battery circuit is broken; but as soon as current is admitted into either coil B and the corresponding shaft C' is turned the corresponding brushes slide off the piece Q' and the local circuit is closed as follows: from the local battery T to the press-magnet M^3 , the frame of the machine, the shaft C' , the disk Q , brush R , back to the local battery. Thus the press-lever is operated by its magnet M^3 every time current is admitted into the coil of either magnet A .

As shown in diagram Fig. 7, relays may be used for the local battery. Each coil B , instead of having its second terminal connected with the earth, as shown in Fig. 5, is connected by a wire e with a relay-magnet f , which in turn is connected with the earth. The armatures g of the relays close the circuit of the local battery T , in which the press-magnet M^3 is arranged. Whenever current passes through either line L' or L^2 to either coil B , the corresponding relay closes the local circuit and the press-magnet operates the printing or pressing lever M .

In place of using but one type-wheel two type-wheels k k' , parallel to each other, may be used, which turn and slide longitudinally together, but bear different type characters. Below each type-wheel a press-plate l l' is located and below them the shiftable presser-head m on one end of a sleeve n , mounted to slide on a rod o . A pivoted lever p engages said sleeve n , so that when said lever is swung to one side or the other the sleeve is shifted and the presser-head m brought under the plate l or l' . At each side of the lever p a permanent bar-magnet q q' is located in such a manner that the north poles face each other, and on the north end of each magnet two coils r r' s s' are secured. The coils r and s and r' and s' are wound and connected so that if a strong positive current passes through the lines L' L^2 the strength of the magnetism is increased in the end X and decreased in the end Z , and if a strong negative current passes through the lines L' L^2 the strength of the magnetism is increased in the end Z and decreased in the end X , and thus

the lever p is shifted to the left or right and shifts the presser-head m correspondingly.

t is a wide inking-ribbon.

If desired, the shafts bearing the type-wheels may carry star-wheels or bevel tooth-wheels, into which a tooth on the press-magnet lever can pass for the purpose of correcting any slight inaccuracies in the positions of the type-wheel.

Having thus described my invention, what I claim as new, and desire to secure by Letters Patent, is—

1. In a printing-telegraph, the combination with a type-wheel mounted to turn and to be shifted in the direction of its length, of a single magnet and its circuit for turning said type-wheel and another single magnet and its circuit for shifting said wheel, a local line, a press-magnet in said local line and means for closing the circuit of the local line from either one or both of the circuits above mentioned, substantially as herein shown and described.

2. In a printing-telegraph, the combination with a type-wheel mounted to turn and to move longitudinally of a single magnet and its circuit for turning said type-wheel and another single magnet and its circuit for shifting said type-wheel, a local circuit, a press-magnet in said local circuit, means for closing the local circuit every time current is admitted to either or both of said two magnet-circuits and a presser and paper-feed mechanism operated by a magnet in the local circuit, substantially as herein shown and described.

3. In a printing-telegraph the combination with a type-wheel mounted to turn and to be shifted longitudinally of two independent magnets and circuits for turning and shifting said type-wheel and two or more resistances acting on the parts moved by each of said magnets independent of the resistances acting on the parts moved by the other magnet, substantially as herein shown and described.

4. In a printing-telegraph, the combination with a type-wheel mounted to turn and to be shifted longitudinally, two independent magnets and circuits for moving said type-wheel of a group of resistances of various strengths acting on parts moved by each of said magnets independent of the resistance acting on the parts moved by the other magnet, substantially as herein shown and described.

5. A printing-telegraph, the combination with a type-wheel mounted to turn and to be shifted longitudinally, of groups of independent mechanical resistances for each magnet, which resistances oppose the power in the magnet for turning and shifting the wheel, and such magnets for so turning and shifting the type-wheel substantially as set forth.

6. In a printing-telegraph the combination with a magnet and circuit, of a shaft turned by said magnet, an arm on said shaft and projecting in opposite directions from the same and series of resistances located at said arm,

at each side of the shaft and at varying distances from said arm, substantially as herein shown and described.

7. In a printing-telegraph, the combination with two independent electric motors and a separate circuit for each; of two adjacent and parallel rotatable and longitudinally-shiftable type-wheels, means operated by said magnets for shifting said type-wheels together and rotating said type-wheels together, a shiftable presser adjacent to said type-wheels and magnets in the circuits of the above-mentioned magnets for shifting said presser, substantially as herein shown and described.

15 8. In a printing-telegraph the combination

with a type-wheel mounted to turn and to be shifted in the direction of its length, of two independent magnets and circuits for turning and shifting said wheel, a third circuit, a press-magnet in said third circuit and means for closing this third circuit from either one or both of the two independent circuits.

In testimony that I claim the foregoing as my invention I have signed my name, in presence of two witnesses, this 31st day of July, 1896.

JOHN BURRY.
